UNITED STATES PATENT OFFICE.

EDWARD H. KRUSE, OF FORT WAYNE, INDIANA.

SECTIONAL SWITCH BOX.

Application filed March 22, 1923. Serial No. 626,729.

This invention relates to improvements in sectional switch boxes of that class provided with removable ends and which may be connected together in assembled groups. 5 The object of the improvement is to provide a construction by which uniform box sections and ends thereof may be assembled together singly or in gangs without the use of screws, rivets or other separable expedients that are ordinarily resorted to for holding the assembled parts together. Another object is to construct the box sections and ends and the securing means therefor so as to leave the top and bottom free from objectionable exterior projections. A further object is to so construct the sections and ends as to admit of their being interchangeably assembled in gangs.

These objects are accomplished by the 20 construction illustrated in the accompanying drawings, in which:—

Fig. 1 is a perspective view of a box section of which the top, back and the bottom of the box embodying the invention is 25 formed;

Fig. 2 is a perspective view of an end-plate interchangeably applicable to the respective ends of the box section; and

Fig. 3 is a plan view of a pair of box sections grouped together with end-plates in 30 position, a portion being broken away.

The characters appearing in the description refer to parts shown in the drawings and designated thereon by corresponding characters.

The invention consists of a metallic box formed of a box section having a top 1, back 2 and bottom 3, and an end-plate 4 for closing each end of said section, the front of the 35 box being open. The top 1 has at its left margin near its front a depression 5, in the center of which is a latch opening 6; the back 2 has in its left margin at its top an opening 7; and the bottom 3 has at its rear end extending outwardly from its left margin a fulcrum 8 having a rearwardly extending hook 9, there being also a latch tongue 10 extending from the left margin of the 40 bottom 3 near its front, said tongue having

an upwardly projecting lug 11. The bottom 50 3 has formed in its right margin near its front a recess 5' and a latch opening 6' in the center thereof; the back 2 has in its right margin at the bottom an opening 7'; and the top 1 has at its rear end extending from its right margin a fulcrum 8' having a rearwardly extending hook 9', there being also a latch tongue 10' extending from the right margin of the top 1 near its front, said tongue having a downwardly projecting lug 11'. The top and bottom each have at their respective front ends oppositely disposed perforated ears 12 for the attachment of a switch member or other device (not shown), such as are ordinarily mounted in boxes of 55 this class.

The end-plate 4 is so formed as to be applicable to either side of the box section by reversing its position according to the side of the section to which it is applied. As illustrated in Fig. 2 the plate has at its upper end near its front a laterally projecting latch tongue 13 having a downwardly protruding lug 14, the tongue being shaped to fit in the depression 5, and the lug 14 being 60 located so as to engage in the latch opening 6 in the top 1. Also, the plate has adjacent its top at its rear margin a laterally projecting fulcrum 8'' having a rearwardly extending hook 9''. In the lower edge of the 65 plate 4 near its front is a notch 15 made for the reception of the latch 10 on the bottom 3, and adjacent the lower edge of the plate at its rear margin is an opening 7'' made 70 for the reception of the hook 9 and fulcrum 8 on the bottom 3. By inverting the plate 4, the notch 15 and opening 7'' have engaging relation respectively with the latch tongue 10' and the hook 9' and fulcrum 8'; and the hook 9'' and the latch tongue 13 75 have engagement respectively in the opening 7' in the back 2 and in the recess 5' in the bottom 3. Thus, the plate may be attached so as to close either one end or other 80 of the box section.

As shown in Fig. 3, two box sections 16 and 17 respectively are connected together and their outer opposite ends are closed re- 85 90 95

spectively by corresponding end-plates 18 and 19. The one box section is secured to the other box section by inserting the hook 9 on the bottom of the section 17 into the opening 7 in the back of the section 16, and simultaneously inserting the hook 9' of the section 16 into the opening 7 of the section 17. When said sections are thus connected and brought together, the latch tongue 10 on the top of the section 16 extends into the cavity 5 in the top of the section 17 and its lug 11' has locking engagement in the latch opening 6 in the top of the section 17. Also, the bottoms of said sections are locked together similarly by the engagement of the lug 11 of the latch tongue 10, on the one section, in the latch opening 6' in the bottom of the other section. In this manner additional sections may be added as required, and end-plates are added to the group of sections at the outer ends of the outermost sections as previously described.

When the sections are connected together the fulcrum 8 on the bottom of one section bears upon the bottom of the adjacent section so that said bottoms are held in a common plane and in locked connection through the medium of the lug 11 on the one section and the latch opening 6' on the other; and the top of the one connected section bears downwardly upon the fulcrum 8' of the other section when the lug 11' of the latter section is engaged in the latch opening 6' in the top of the former section. The sections being composed of thin sheet metal admits of their tops and bottoms being sprung sufficiently out of normal position to effect the engagement of their respective latch members in the corresponding latch openings, the fulcrums tending to sustain the locked connections between the connected tops and between the connected bottoms by holding the same alined in corresponding common planes.

45 What I claim is:—

1. In a switch box, a section having top, bottom and back portions forming the corresponding parts of the box, said top portion having in its left margin near the front a depression and latch opening therein and having at its opposite edge a laterally projecting latch tongue with a downwardly projecting lug, and having also at its rear end a laterally projecting fulcrum with a rearwardly extending hook, said back portion having an opening at its upper left corner and lower right corner, and said bottom portion having at its left edge near its front a laterally projecting latch tongue with an upwardly projecting lug, and also at its rear end a laterally projecting fulcrum with a rearwardly extending hook, the opposite edge of said bottom portion having near its front a recess and latch opening therein; and an end-plate interchangeably applicable

to the sides of said section, the top of said plate having a laterally projecting latch tongue with a downwardly extending lug and also at its rear end a laterally projecting fulcrum with a rearwardly extending hook, there being in the lower end of said plate a notch for the reception of the latch tongue of said bottom portion and an opening for the reception of the corresponding fulcrum and hook. 75

2. In a switch box, a section having integral top, back and bottom portions forming the corresponding parts of the box, said top and bottom portions each having in opposite arrangement a latch member at one side and a latch opening at its opposite side and having also at one side a rearwardly extending hook, there being an opening in each end of said back portion near the side thereof opposite the hook on the adjacent portion; and a plate for closing each side of said section, each plate having at its top and bottom means for engagement with the latch member, hook, hook opening and latch opening at the corresponding side of said section. 85 90

3. In a sectional switch box, a section having a back portion and top and bottom portions contiguous with the back portion, each edge of said section having a latch member, hook member, hook opening and latch opening arranged relatively in the reverse order of succession to those of the opposite side; and a plate for closing each side of the section, each plate having at one end a latch member and hook member for engagement respectively with the latch opening and hook opening at the corresponding side of said section, and at its opposite end a hook opening and a notch respectively for the reception of the corresponding hook and latch member on said section. 95 100 105

4. In a sectional switch box, a section having a back portion and top and bottom portions contiguous with the back portion, each edge of said section having a latch member, hook member, hook opening and latch opening arranged relatively in the reverse order of succession to those of the opposite edge; and a plate engageable with said latch member, hook member, hook opening and latch opening on either edge of said section interchangeably, said hook members being located adjacent said back portion respectively on the top and bottom portions, and said hook 110 115 120 125 openings being made in the back portion respectively adjacent to the top and bottom portions, opposite the corresponding hook members, the latch member and latch opening on the top and bottom portion being located adjacent the front ends thereof.

5. In a switch box, a section having integral top, bottom and back portions forming the corresponding parts of the box, said top and bottom portions each having ex- 130

tending from their relatively opposite sides adjacent the back portion a lateral fulcrum member with a rearwardly extending hook, said back portion having therein a hook opening at its top and bottom adjacent the sides thereof opposite said fulcrum members, said top and bottom portions having 5 near their forward ends at each side thereof

a latch means; and a plate for closing each side of said section, each of which has means in connection therewith engageable with the fulcrum member, the hook opening and the latch means of the corresponding side of said section. 10

In testimony whereof I affix my signature.

EDWARD H. KRUSE.
